UNITED STATES PATENT OFFICE

149,830

DESIGN FOR AN AUTOMOBILE FRAME

Charles P. Nelson, Santa Monica, Calif.

Application January 28, 1947, Serial No. 136,467

Term of patent 14 years

(Cl. D14—3)

To all whom it may concern:

Be it known that I, Charles P. Nelson, a citizen of the United States of America, residing at Santa Monica, in the county of Los Angeles and State of California, have invented a new, original, and ornamental Design for an Automobile Frame, of which the following is a specification, reference being had to the accompanying drawing, forming part thereof.

The figure is a perspective view of a tubular automobile frame, showing my new design.

I claim:

The ornamental design for an automobile frame, as shown.

CHARLES P. NELSON.
